SERVING FORK OR THE LIKE

Clayton A. Laughlin, Minneapolis, Minn.
(8749 S. Greenwood Ave., Chicago, Ill. 60619)

Filed May 2, 1966, Ser. No. 2,111

Term of patent 14 years

(Cl. D54—12)

FIG. 1 is a top plan view of a serving fork incorporating my new design;

FIG. 2 is a vertical sectional view thereof taken on the line 2—2 of FIG. 1; and

FIG. 3 is a horizontal sectional view thereof taken on the line 3—3 of FIG. 1.

The dominant features of the design reside in the full line portions of the drawing.

I claim:

The ornamental design for a serving fork or the like, substantially as shown and described.
